UNITED STATES PATENT OFFICE.

THOMAS H. DONOHUE, OF WASHINGTON, DISTRICT OF COLUMBIA.

MANHOLE CLOSURE.

Application filed May 26, 1920. Serial No. 384,420.

To all whom it may concern:

Be it known that I, THOMAS H. DONOHUE, a citizen of the United States, residing at Washington, in the District of Columbia, 5 have invented certain new and useful Improvements in Manhole Closures, of which the following is a specification.

This invention relates to certain new and useful improvements in manhole closures.

10 Heretofore it has been customary to employ a cast-iron ring which is set over the top of the manhole, after which asphalt or other material such as concrete used for the street or pavement surface, is then applied 15 over and upon the top of the base of the ring. When it is found necessary to remove the ring, for example in replacing the transformer in electric conduit work, the asphalt or concrete must be laboriously dug up and 20 from about the ring. This leaves a large hole or broken-up area in the street, which after the ring has been again replaced, must be repaired by filling in with asphalt or concrete in order to restore the street surface to 25 its former condition. The street repair work can, in certain municipalities, be done only by the municipal authorities, and consequently it not infrequently occurs that a considerable period elapses before the street 30 can be repaired by such authorities. In the meantime, the electric light or telephone company operating the manhole is responsible or liable for any damages resultant from the condition of the street pending repair 35 of the latter. Usually temporary filling matter is used by the company in the aforementioned instances until the proper authorities can effect permanent repairs to the street.

40 The present invention therefore aims to provide a closure which eliminates all of the foregoing objections and briefly resides in a unitary structure composed of a concrete base the top surface of which is finished to 45 form a part of the street or pavement surface and a manhole cover frame about which the base is molded, so that the base and therewith the frame can be bodily dislodged or removed from the street and then re- 50 placed without the necessity of cutting up the street except as concerns a slight cut of about one-half an inch marginally of the base so as to allow the latter to be lifted out of place. Upon replacement, grout, or other 55 suitable semi-liquid filler may be poured in the cut and the joint will then be completed

and rendered fit for service upon mere hardening, thus eliminating the use of a temporary filling and also saving the expense of resurfacing the street contiguous to the man-hole. 60

The invention further aims to provide a closure which will support the cast-iron frame so as to prevent breakage thereof due to vehicular traffic imposing static pressure and strains or stresses thereon. 65

Further and other objects will be later set forth and manifested in the course of the following description.

In the drawings:

Figure 1, is a top plan view of the invention:

Figure 2, is a section on line 2—2 of Figure 1, and

Figure 3, is a fragmentary sectional view 75 of a modified form of the invention.

In proceeding in accordance with the present invention, a concrete base 1, is employed which as depicted in Figure 1, has a preferably square formation and is equipped with reinforcing rods 2, which are superimposed 80 upon each other in hollow square formation and upon which in turn is superimposed the cast-iron ring or frame 3, the latter receiving the cover, not shown. Wings, flanges, fins or webs 4, extend radially of the ring 85 and are preferably of less height than that of the ring, the lower faces of the webs also seating on the reinforcing rods as depicted in Figure 2, of the drawings. The lower or bottom edge of the ring, at points between 90 the webs 4, is cut-away in curved formation as depicted in Figure 2, so that a part of the concrete base will project up into the ring to thereby provide a thickened part of the base 95 for supporting the ring so as to prevent breakage due to vehicular or other traffic occurring over the base and ring.

As shown in Figure 3, of the drawings the concrete may terminate below the top of the metal so that an asphalt top covering 100 5 may be applied to correspond to streets or walks paved with this material.

In Figure 1, the seam S between the street surface, i. e. the surface of the pavement or the drive and the base is filled with liquid 105 grout, so that in removing the base in cases where the transformer is to be removed and a new one or another installed, it is merely necessary to remove the seam and then the base, which may be done by force exerted 110 from both above and below the base. Consequently, when the base is replaced or

placed back into position, it is merely necessary to pour grout into the seam, which upon hardening completes the work and entirely eliminates all of the foregoing objections heretofore presented.

Further, the invention may be used with rectangular manholes and in this use the customary I-beams for supporting the iron-ring heretofore used, are dispensed with, 10 the base spanning the width of the manhole and itself taking the place of the I-beams for supporting the iron-ring heretofore used, the base spanning the width of the manhole. The spaces at the ends of the base are easily 15 filled with concrete by use of forms, or single boards, since such spaces do not exceed a few inches in width.

What is claimed is:

In a manhole closure for electric conduits 20 and the like, a concrete base having a central opening and a metal cover-receiving frame

embedded in the base and forming a lining for the central opening, said frame having a cover-seat disposed below the upper face of the concrete base, webs extending outwardly 25 from the frame and into the base, said base being formed so as to provide a covering for the manhole and to leave a seam-forming space between the marginal edges of the base and the street surface contiguous thereto whereby the base is bodily removable from over the manhole without breaking up 30 of the street surface, the base having its top surface finished to lie flush with the street surface and to provide a continuation thereof, and a removable filler for said seam-forming space, said seam-forming space being of substantial width, so as to allow the 35 filler to be removed without disturbing the base or the street surface contiguous thereto. 40

In testimony whereof I affix my signature.

THOMAS H. DONOHUE.
